(57) **CLAIM**

The ornamental design for the illuminated speaker pod, as shown and described herein.

DESCRIPTION

FIG. 1 is a top, front, right side perspective View of an illuminated speaker pod shown in a non-illuminated state, according to an embodiment of the present disclosure;

FIG. 2 is a top, rear, left side perspective view of the illuminated speaker pod shown in FIG. 1;

FIG. 3 is a front view of the illuminated speaker pod shown in FIG. 1;

FIG. 4 is a rear view of the illuminated speaker pod shown in FIG. 1;

FIG. 5 is a left side view of the illuminated speaker pod shown in FIG. 1;

FIG. 6 is a right side view of the illuminated speaker pod shown in FIG. 1;

FIG. 7 is a top view of the illuminated speaker pod shown in FIG. 1;

FIG. 8 is a bottom view of the illuminated speaker pod shown in FIG. 1; and,

FIG. 9 is a top, front, right side perspective view of an illuminated speaker pod shown in an illuminated state, according to a second embodiment of the present disclosure, which is structurally equivalent to the embodiment of FIG. 1, but further includes groups of four radiating lines representing illumination from portions of the illuminated speaker pod. The groups of four radiating lines form no part of the claimed design.

The broken lines in the drawings are included to show portions of the article that form no part of the claimed design.

1 Claim, 8 Drawing Sheets
